UNITED STATES PATENT OFFICE

SALVATOR CEFALU AND ANDREW CEFALU, OF BROOKLYN, NEW YORK

PERMANENT WAVE DEVICE

Application filed April 26, 1932. Serial No. 607,606.

This invention relates to permanent wave devices.

Our present invention is an improvement on the waving device shown in Patent No. 5 1,850,789 and is designed to produce a permanent wave of a natural type. The embodiment of the present invention is also simpler than the apparatus shown in the mentioned patent and also embodies novel 10 means for securing the hair to the device.

The invention will be fully and comprehensively understood from a consideration of the following detailed description when 15 read in connection with the accompanying drawing which forms part of the application with the understanding, however, that the improvement is capable of extended application and is not confined to the exact 20 showing of the drawing nor to the precise construction described and, therefore, such changes and modifications may be made therefrom as do not affect the spirit of the invention nor exceed the scope thereof as expressed in the appended claims.

In the drawing:

Fig. 1 is a plan view of the device, the casing being partly broken away.

Fig. 2 is an elevational view, partly in section, of the device shown in Fig. 1.

Fig. 3 is a detailed view of an end portion of the device removed from the casing, this view being partly in section and showing the hair associated with the device for waving 35 purposes.

Fig. 4 is a section taken on the line 4—4 of Fig. 3; and

Fig. 5 is a section taken on the line 5—5 of Fig. 3.

Referring to the drawing for a more detailed description thereof, the device comprises a plurality of parallel bars or rods 7, adjacent bars being connected by transverse members 8 which may be, and preferably are, 45 integral with the bars 7. The mentioned bars and connecting members 8 thus form a single element. The hair is wound in opposite directions on adjacent bars, as shown in Fig. 4, and is held to said bars by means of clamping sleeves 9 open at one side, as indi-

cated by the numeral 10, the open sides of adjacent sleeves being in opposite positions, as clearly shown in Fig. 4. The end bars 7 are shorter than the corresponding intermediate bars, as shown in Fig. 1, and these end bars have hollow extensions 11 extending at right angles thereto and accommodate bushings 12. Said bushings have flanges 13 at their outer ends and said flanges abut against the ends of the extensions 11 and are held in place by screws 14 which threadedly engage the inner end portions of the bushings and are provided with heads 15 of greater diameter than the bushings in order to contact the inner ends of the extensions and thereby hold the bushings in place. Tapered terminals 16, having slots 17 formed lengthwise therein, are provided with stems 18 which are each rotatable in only one direction within their respective bushings 12, said stems 18 carrying pins 19 which pass diametrically therethrough and are bent at their ends and pointed, as shown in Fig. 5, in order to allow the terminals to be turned in only one direction, the interiors of the bushings being preferably roughened where the sharpened ends of the pins contact them.

The hair to be waved is preferably secured to each of the terminals, as shown in Fig. 3, by means of a string or cord 21 secured to the hair and to the terminal, the string or cord being wound around the terminal and passing through the slot 17 therein. By turning the terminals 16 until the ends of the hair are adjacent thereto, the strings 21 being thereby wound around the terminals, said ends will be held in position on the device.

After the hair has been properly positioned and clamped on the device, a damp or wet flannel is preferably wrapped around the same and a casing 23, having an electric heating element 24 at the top and bottom thereof, is placed over the device on which the hair is positioned, said casing carrying a heat regulating knob 25, as shown in Fig. 2, there being a dial 26 under and adjacent the knob 25 to indicate the degree of heat developed in the device when the knob is in a particular position.

What is claimed is:

1. A permanent wave device comprising a series of bars, clamping sleeves on said bars and terminals on the end bars of the series, said terminals each comprising a member rotatable only in one direction and adapted to hold fastening means.
2. A permanent wave device comprising a series of connected, parallel bars, clamping sleeves on said bars and terminals on the end bars of the series, said terminals each comprising a member rotatable only in one direction and adapted to hold fastening means.
3. A permanent wave device comprising a series of bars, clamping sleeves on said bars and terminals on the end bars of the series, said terminals each comprising a member rotatable only in one direction and adapted to hold fastening means, a casing for said bars and electric heating means within said casing.
4. A permanent wave device comprising a series of bars, open-sided clamping sleeves on said bars and terminals on the end bars of the series, said terminals each comprising a member rotatable only in one direction and adapted to hold fastening means.

In testimony whereof we hereby affix our signatures.
